UNITED STATES PATENT OFFICE.

EVERETT P. LEONARD, OF CHATTANOOGA, TENNESSEE.

TAKE-UP MECHANISM FOR KNITTING MACHINES.

Application filed July 20, 1922. Serial No. 576,193.

To all whom it may concern:

Be it known that I, EVERETT P. LEONARD, a citizen of the United States, residing at Chattanooga, in the county of Hamilton and State of Tennessee, have invented certain new and useful Improvements in Take-Up Mechanism for Knitting Machines, of which the following is a specification.

This invention relates particularly to take-up mechanism for knitting machines which produce a tubular knitted fabric; but the mechanism is also applicable to knitting machines producing knitted fabrics in other forms.

The object of this invention is to provide a take-up mechanism which is adapted to draw uniformly on the knitted fabric and thus avoid excessive strain or excessive slackness on the thread or yarn at the needles, regardless of variations or irregularities in thickness of the knitted fabric itself or of the finished product consisting of such a composite fabric structure as is hereinafter described.

Thus my improved take-up mechanism is adapted to draw with appropriate tension a knitted fabric of uniform thickness or a fabric structure, portions of which are thick and other portions of which are thin, as, for example, a fabric structure comprising a tubular knitted fabric and sections of cotton batting or similar masses of cotton surrounded by the knitted fabric and spaced from each other to leave portions of the knitted fabric empty, the knitted fabric being afterward cut transversely midway between the masses of cotton batting, this transverse cutting being the last step in the making of sanitary napkins.

To fit the take-up mechanism to engage the tubular knitted fabric containing such masses of cotton spaced from each other requires a mechanical organization embodying co-operating pressure rolls which are automatically adjustable transversely to suitably engage the thin parts and the thick parts of the composite fabric structure, the rolls being also adapted to yield up and down toward and from the knitting mechanism.

To these ends, my improved mechanism includes a group of feed rolls which are inter-related for horizontal movement relative to each other and for up and down movement relative to the knitting mechanism, said rolls forming a throat or course

for the fabric issuing from the knitting mechanism.

In the accompanying drawings,

Fig. 1 is a side elevation of a mechanism embodying my improvement;

Fig. 2 is a similar view, a part being in upright section;

Fig. 3 is a horizontal section on the line, 3-3, of Fig. 1;

Fig. 4 is a larger detail elevation with the cog gear wheels of Fig. 1 broken away;

Fig. 5 is a detail elevation looking at the side of the mechanism opposite the side shown by Fig. 4;

Fig. 6 is a horizontal section on the line, 6-6, of Fig. 5;

Fig. 7 is a view of the front side of a composite fabric structure adapted to be cut into sections to form sanitary napkins.

Referring to said drawings, A indicates the usual rotary knitter head of a conventional circular knitter. B is the usual rotary spool table and usual thread guide construction all turning with the rotary head. C designates any suitable supporting frame for the knitting mechanism, the feeding mechanism, cutting mechanism, drawing-off mechanism and the shafting and gearing of such mechanisms.

Actual experience has demonstrated that when but one pair of driven spring-pressed drawing-off rolls is employed they will not take hold promptly of the thicker or pad-stuffed portions of the product or tubing, but occasion a pause and back-slipping in the drawing-off operation, allowing the loops to slip off from the needle of the knitting head and so are impractical. It is found that two pairs of spring pressed rolls, preferably both constantly positively driven, mounted so as to grip the tubular product and draw it off under tension and to maintain uniform tension by their ability to slightly change position as a unit as the knitting proceeds and the tension or slack tends to vary will meet the situation, this construction obviously providing for at least two opposing drawing-off rolls, or one half of the drawing-off mechanism, at all times gripping and pulling off the finished product.

As one suitable construction, found by actual use to be satisfactory, I have illustrated a pivoted supporting frame having a bifurcated or forked end or yoke, 61, and a mounting and weight arm, 62, having the usual notches in its upper edge to receive the wire

or hook or bail of the usual counter-balance weight, 63, and pivotally mounted by a pin or pintle, 64, in the frame C.

Each arm of the yoke, 61, is bifurcated or slotted as at, 65, the bifurcations being closed, for instance, by plates, 66, secured in position by any suitable means. The upper rolls, 67 and 68, are mounted between said yoke arms and have their shafts, 69 and 70, respectively, resting in the slots, 65, of the said arms so as to slide sidewise and longitudinally in the slots toward and away from each other. Upright link or radius arms, 71, freely hung upon each shaft, 69 and 70, and adjacent each end thereof inside of the arms of said yoke, 61, carry in their lower ends, respectively, the shafts, 72 and 73, of the lower rolls, 74 and 75.

The shafts, 69, 70, 72 and 73 have mounted upon them sprocket wheels, 76, 77, 78 and 79, respectively, all four of said sprocket wheels lying in the same vertical plane passing between the arms of said yoke, 61, and between the ends of the rolls, 67 and 68, and the adjacent arm of said yoke, 61, and being secured upon their respective shafts to turn therewith.

A sprocket chain, 80, passing over sprocket wheels, 76 and 78, causes rolls, 67 and 74, to rotate together and in the same direction; and a sprocket chain, 81, passing over sprocket wheels, 77 and 79, causes rolls, 68 and 75, to rotate together and in the same direction, the direction of rotation of these latter rolls being reversed relative to the direction of rotation of rolls, 67 and 74.

The shafts, 69 and 70, are each provided, outside of said yoke, 61, with double cog gears, 82 and 83, respectively, the two series of teeth of each double gear being arranged in over-lapping relation and being long and large, this construction permitting the shafts, 69 and 70, to move toward or from each other as the rolls, 67 and 68, move to accommodate the varying thicknesses of the article being drawn off without said gears, 82 and 83, losing mesh with each other and without any appreciable lost motion in the transmission of power by gear, 82, to gear, 83.

A pinion or worm gear wheel, 84, is mounted on the shaft, 69, lying between the arms of the yoke, 61, to turn with said shaft. Closely adjacent to one of the arms of said yoke, 61, a gear worm, 85, is in mesh with the worm wheel, 84, and is supported on a shaft, 85^a, which rests in brackets, 86, extending from the adjacent arm of said yoke, 61. The shaft of the gear worm is provided on its rear end with a bevel gear, 87, keyed to said shaft and meshing with a bevel gear, 88, fixed on and rotating with the shaft, 89, carried by said arm, 62, and rising and falling with said arm, 62, and yoke, 61. The pulley or belt wheel, J, is fixed on the other

end of said shaft, 89. The driving belt, K, passing around pulley, J, drives said pulley.

The rolls, 67 and 68, rotating in opposite directions and their meeting faces moving downward and the rolls, 74 and 75 similarly 70 rotating in opposite direction and their meeting faces moving downward, the rolls of each pair are by any suitable means pressed toward the rolls of the other pair. As one satisfactory way, so demonstrated by 75 use, of accomplishing this object, I have illustrated a perforated lug, 90, projecting laterally from the outer surfaces of the medial portion of each link arm, 71, preferably adjacent the adjacent edges of each end 80 pair of the links. A rod, 91, is then passed through each of the perforated lugs, 90, of each of the respective end pairs of link arms, 71. A helical expanding spring, 92, is then passed over each end of each rod, 91, until it 85 strikes its respective lug, 90. A nut, 93, is then screwed on each end of each rod, 92, a uniform distance until the desired degree of spring compression is obtained.

This normally forces the rolls, 67 and 68, 90 and the rolls, 74 and 75, respectively, yielding toward each other with uniform pressure, but allows either roll of either pair of rolls, 67 and 74, or 68 and 75, to move toward or away from the opposing roll to accommodate themselves to varying thicknesses of the article being drawn-off without affecting the relative relation of the other opposing rolls or without affecting their grip upon the material being drawn off. 100

The weight, 63, is to be suspended from any one of several points on one side of the pivotal line, 64, and said weight will partially counterbalance, to a degree according to the point from which it is suspended, the 105 total weight of the yoke, 61, the pulley, J, rolls 67, 68, 74 and 75, and their associated elements, located on the other side of the pivotal line, these rising slightly in case of any tendency toward unusual tension upon 110 the material being drawn-off, easing up on it, and falling slightly in case of any tendency toward slack of the material being drawn off, thus maintaining, so far as is possible, uniform tension upon the material 115 being drawn off and guarding against any slack which would otherwise permit the loops to slip off of the knitting needles, the rising and falling motion mentioned being so slight as not to cause such a degree of slack in the belt, K, as would affect the driving engagement of the latter with the pulley, J.

The assemblage as illustrated is especially intended for use in the automatic large volume production of sanitary napkins as finished articles, save for the actual cutting apart of the individual pad portions for immediate use, without need for any sewing, folding, pasting or other operation or oper- 125 130

ations, the fabric of the tubing receiving the pads being knitted with comparatively large openings, as illustrated in Figures 6 and 7.

However, I have found that this combination of mechanisms may, with suitable adjustments, be used to turn out a new article for use in hospitals and in surgical work, it being especially of value for use as a bandage for broken arms and limbs without the need of the objectionable annoying and clumsy rigid or semi-rigid splints now in general use for such purposes, the said surgical article being illustrated in Figure 8 of the drawings and being composed of a strip of cotton-batting or other suitable flexible padding material inside of the knitted tubular fabric and which may be many feet in length and put up in roll form, as illustrated, or packed in lengths of from three to six or twelve or more feet.

It will now be observed that the four rolls are interrelated in such manner as to cause them to act upon each other and form a throat for the passing of the fabric. The rolls at each side of the fabric constitute a pair mounted on upright supports which are adapted to rock and also to move bodily toward and from the fabric, whereby the two upper rolls may automatically separate farther than the two lower rolls are separated, and vice versa, whereby all the rolls appropriately engage the fabric regardless of the thickness of the part of the fabric at the time between two opposing rolls. At the same time, the rocking member, 62, permits the group of rolls to yield up and down in unison for maintaining a substantially uniform tension on the fabric or fabric structure. It may be said that the rolls of either pair and their supporting links constitute a "floating" structure and that the four rolls and their supporting means collectively constitute a "floating" structure.

As above stated, the four rolls are closely associated to form a co-operating group. It may be said that these rolls form a multiple group. The axial lines of the lower rolls are close to the axial lines of the companion upper rolls, whereby the distance between the engagement of the upper rolls and the engagement of the lower rolls with the fabric structure is made less than the length of the cotton batting sections which form thick parts of the fabric structure. At the same time the distance between the said axial lines is more than the distance between the batting sections, whereby the distance between the engagement of the upper rolls and the engagement of the lower rolls is made greater than the space between the batting sections in the fabric structure, whereby the making of the two engagements between the batting sections and on the empty knitted tube is avoided. Hence during the passing of the fabric structure, a thick part (a part con-

taining a batting section) is at all times engaged and being drawn by at least two opposing rolls. Thus the dominating drawing action is constantly exerted through a quick part of the fabric structure.

I claim as my invention,

1. In combination with a knitting machine, two laterally yielding supporting means, and a pair of drawing rolls on each of said supporting means, said rolls forming a throat for the fabric, substantially as described.

2. In combination with a knitting machine, a rocking frame, two laterally yielding supporting means on said frame, and a pair of drawing rolls on each of said supporting means, said rolls forming a throat for the fabric, substantially as described.

3. In combination with a knitting mechanism, a plurality of pairs of associated laterally yielding drawing rolls forming a throat for the fabric, and a common pivoted supporting frame supporting said rolls to permit simultaneous up-and-down movement according to variation in fabric strain, substantially as described.

4. In combination with a knitting mechanism, a plurality of pairs of associated and co-operating rolls forming a throat for the fabric, and a common pivoted supporting frame supporting said rolls to permit simultaneous up-and-down movement according to variation in fabric strain, substantially as described.

5. In combination with a knitting mechanism, a pair of rolls at each side of the fabric course, and relatively laterally yielding links supporting said rolls, substantially as described.

6. In combination with a knitting mechanism, a pair of rolls at each side of the fabric, relatively laterally yielding and rocking links supporting said rolls, substantially as described.

7. In combination with a knitting mechanism, a pair of rolls at each side of the fabric course, relatively laterally yielding links supporting said rolls, and a common pivoted supporting frame supporting said rolls to permit simultaneous up-and-down movement according to variation in fabric strain, substantially as described.

8. In combination with a knitting mechanism, a pair of rolls at each side of the fabric, relatively laterally yielding and rocking links supporting said rolls, and a common pivoted supporting frame supporting said rolls to permit simultaneous up-and-down movement according to variation in fabric strain, substantially as described.

9. In combination with a knitting mechanism, a pair of co-operating rolls at each side of the fabric course, the axles of the upper rolls being relatively sidewise shiftable, links suspended from said axles and form-

- 4
- ing supports for the lower rolls, and horizontal coupling means joining said links between their ends, substantially as described.
5. 10. In combination with a knitting mechanism, a pair of co-operating rolls at each side of the fabric course, the axles of the upper rolls being relatively sidewise shiftable, links suspended from said axles and forming supports for the lower rolls, and horizontal coupling means yieldingly joining said links between their ends, substantially as described.
10. 11. In combination with a knitting mechanism, a common pivoted supporting frame, a pair of co-operating rolls at each side of the fabric course, the axles of the upper rolls being relatively shiftable sidewise on said frame, links suspended from said axles and forming supports for the lower rolls, and means yieldingly forcing said links toward each other, substantially as described.
15. 12. In combination with a knitting mechanism, a common pivoted supporting frame, a pair of co-operating rolls at each side of the fabric course, the axles of the upper rolls being relatively shiftable sidewise on said frame, links suspended from said axles and forming supports for the lower rolls, and horizontal coupling means yieldingly joining said links between their ends, substantially as described.
20. 13. In combination with a knitting mechanism, two laterally yielding supporting means, a pair of laterally-yielding drawing rolls on each of said supporting means said rolls forming a throat for the fabric, and chain gearing connecting the axles of the rolls of one pair and chain gearing connecting the axles of the rolls of the other pair of rolls, substantially as described.
25. 14. In combination with a knitting mechanism, a plurality of pairs of associated and co-operating rolls forming a throat for the fabric, chain gearing connecting the axles of the rolls of one pair and chain gearing connecting the axles of the rolls of the other pair of rolls, substantially as described.
30. 15. In combination with a knitting mechanism, a common pivoted supporting frame, a pair of co-operating rolls at each side of the fabric course, the axles of the upper rolls being supported in said frame, chain gearing connecting the axles of the upper roll of one pair of rolls with the axle of the lower roll of said pair, a worm gear wheel on said upper axle, a gear worm supported by said frame and meshing with said worm gear wheel, and a driving wheel supported by said frame in operative relation with said gear worm, substantially as described.
35. 16. In combination with mechanism for forming the herein described sanitary napkin structure, a pair of co-operating rolls at each side of the fabric course, the distance between the axial lines of each pair of rolls being less than the length of the batting sections in the fabric structure and more than the distance between the adjacent ends of said batting sections, substantially as described.
40. 17. In combination with a knitting mechanism, a multiple group of closely associated rolls forming a plurality of lateral co-operating pairs of laterally yielding rolls, substantially as described.
45. 18. In a drawing-off mechanism, two pairs of superposed rolls, inter-meshing gears mounted to turn with the upper rolls, links depending from the shafts of the upper rolls, lower rolls mounted in said links, means for driving each lower roll from the companion upper roll, and yielding means for forcing the rolls of each pair toward the rolls of the other pair, substantially as described.

EVERETT P. LEONARD.
